BOTTLE CLOSURE RETAINER

Wilbert W. Mays, Steelton, Pa.

Application December 1, 1943, Serial No. 512,507

6 Claims. (Cl. 215—98)

The present invention relates to the art of bottle closures and it particularly has for its object to provide a simple, effective and inexpensive means for preventing unauthorized removal of the corks or stoppers from liquor bottles, medicine bottles, etc.

Generally the invention includes a device that may be fitted over the neck and mouth of a bottle and secured to the neck and over the cork or stopper, with very little effort.

Other objects will in part be obvious and in part pointed out hereinafter.

To the attainment of the aforesaid objects and ends the invention still further resides in the novel details of construction and arrangement of parts, all of which will be described in the following detailed description, and then be pointed out in the appended claims, reference being had to the accompanying drawing in which:

Fig. 1 is a vertical longitudinal section of a bottle neck and my invention placed thereon, the parts being in the released or inoperative position.

Fig. 2 is a top plan view of the securing ring.

Fig. 3 is a top plan view of the upper outer sleeve.

Fig. 4 is a top plan view of the lower outer sleeve.

Fig. 5 is a top plan view of the lower inner sleeve.

Fig. 6 is a top plan view of the upper inner sleeve.

Fig. 7 is a top plan view of one half of the neck clamp element.

Fig. 8 is an inverted plan view of one of the cap halves.

Fig. 9 is a view similar to Fig. 1 showing the parts in the operative position.

In the drawing, in which like numerals of reference indicate like parts in all the figures, 1 indicates a bottle whose neck 3 has an outside annular bead 2. The usual stopper or cork is indicated at 4.

The device which comprises my invention includes a bottom inner sleeve 5 externally threaded (left hand) as at 6 and having diametrically opposite bifurcated brackets 9 at the lower end of the sleeve. The upper end of the sleeve 5 is reduced as at 7. The part 7 is externally threaded at 8. The lower inner sleeve 5 rests on the bead 2 as shown.

An upper inner sleeve 26 having an internally threaded portion 29 fits on the reduced extension 7 and is externally threaded as at 28 (right hand). It also has diametrically opposite re-

cesses 27 in which the arms 24 are pivoted at 25. The arms 24 are preferably externally threaded with threads registering with the threads 28 when the parts are in their operative positions (Fig. 9).

Pivoted at 10 in the brackets 9 are the arms 11 which carry the half-collar clamping elements 12.

13 indicates a lower outer sleeve whose internal threads 16 engage the external threads 6 of the lower inner sleeve 5. The sleeve 13 has external splines 14 which engage the grooves 18 in the upper outer sleeve 17. The sleeve 17 has a flange 19 at its upper end with an annular row 15 of holes 20 to cooperate with like holes 21 in an internally threaded ring 22 that is threaded on the inner upper sleeve 26.

The arms 24 carry cover members 23 which, when in operative position, fit together over the mouth of the bottle prevent access to the cork 4.

The sleeve 26 has a flange 31 at its lower end to limit the lower travel of the ring 22 on the sleeve.

With the parts in the position of Fig. 1, in order to close the covers 23 over the bottle mouth and retain them in place, the ring 22 is screwed upward to the position shown in Fig. 9; then sleeves 13 and 17 are screwed upwardly to position the clamps 12 together as a ring around the bottle neck below the bead 2; the flange 31 serving as a stop for the sleeve 13. The flange 15 on the sleeve 13 engages the short ends of the pivoted arms 11, when the sleeve 13 is screwed up to the position of Fig. 9, to force the clamps 12 into gripping engagement with the bottle and hold them there below the bead 2. Next the sleeve 17 is raised until its flange 19 engages the ring 22, whereupon the loop of the padlock 30 is placed through aligning holes 20, 21 and 40 locked, thus preventing opening of the device.

From the foregoing description taken in connection with the accompanying drawing it is thought the construction, operation and advantages of the invention will be clear to those skilled in the art.

What I claim is:

1. The combination with a bottle neck having an external bead and a stopper: cover members; a support embracing the bottle neck to which 50 support said members are hinged; a bottle neck gripper carried by said support; and means mounted on said support for applying said gripper into holding contact with said neck below said bead; means for holding said cover members closed; and means for securing said gripper

applying means unmovably in a gripper applying position.

2. The combination with a bottle neck having an external bead and a stopper: cover members; a support embracing the bottle neck to which support said members are hinged; a bottle neck gripper carried by said support; and means mounted on said support for applying said gripper into holding contact with said neck below said bead; means mounted on said support and movable to a position to close said cover members; and means for securing said last named means and said gripper applying means in a position to hold the gripper applied and the cover closed.

3. The combination with a bottle neck having an external bead and a stopper: cover members; a support embracing the bottle neck to which support said members are hinged; a bottle neck gripper carried by said support; and means mounted on said support for applying said gripper into holding contact with said neck below said bead; means mounted on said support and movable to a position to close said cover members; and means for securing said last named means and said gripper applying means in a position to hold the gripper applied and the cover closed, said securing means including a lock.

4. A device of the class described including; a lower inner sleeve adapted to encircle a bottle neck; an upper inner sleeve secured to said lower inner sleeve and also adapted to encircle the bottle neck; at least one cover member mounted on said upper inner sleeve for movement over the mouth of a bottle; a bottle neck gripper mounted on said lower inner sleeve; means mounted on said inner lower sleeve for operating said gripper to clamp and release, respectively, its grip on a bottle neck; and means to secure said last named means and said cover member in their respective bottle-closed positions for purposes described.

5. Means for preventing removal of a stopper from a bottle having a neck with a bead below the mouth of the bottle: including; a sleeve shaped to encircle the bottle neck above and rest on the bead, said sleeve including a lower element having an external left hand thread and an upper element having an external right hand thread; brackets carried by said lower element; a bottle neck gripper comprising two half-collars carried by arms which are pivoted to said

brackets, said half-collars being shaped to embrace the bottle neck below the bead thereof; a lower outer sleeve threaded on said lower element and movable thereon within the limits of the length of said lower element, said lower outer sleeve having means to engage said arms to apply said half-collars to the bottle neck; an upper outer sleeve mounted on said lower outer sleeve and said upper outer sleeve telescopic, said lower outer sleeve having a spline-groove connection and said upper outer sleeve having a flange; cover members swingably mounted on said upper element; a ring threaded on said upper element for holding said cover members closed, said ring and said flange having holes positioned to register with one another to receive the loop of a padlock when said ring and said flange are adjacent one another for purposes described.

6. Means for preventing removal of a stopper from a bottle having a neck with a bead below the mouth of the bottle: including; a sleeve shaped to encircle the bottle neck above and rest on the bead, said sleeve including a lower element having an external left hand thread and an upper element having an external right hand thread; brackets carried by said lower element; a bottle neck gripper comprising two half-collars carried by arms which are pivoted to said brackets, said half-collars being shaped to embrace the bottle neck below the bead thereof; a lower outer sleeve threaded on said lower element and movable thereon within the limits of the length of said lower element, said lower outer sleeve having means to engage said arms to apply said half-collars to the bottle neck; an upper outer sleeve mounted on said lower outer sleeve telescopic, said lower outer sleeve and said upper outer sleeve having a spline-groove connection and said upper outer sleeve having a flange; cover members swingably mounted on said upper element; a ring threaded on said upper element for holding said cover members closed, said ring and said flange having holes positioned to register with one another to receive the loop of a padlock when said ring and said flange are adjacent one another for purposes described; said cover members having threaded arms and said ring being adapted to screw onto said arms when the cover members are closed to hold the cover members in closed position.

WILBURT W. MAYS.
